UNITED STATES PATENT OFFICE.

HOMER W. KRUSE, OF HEALDSBURG, CALIFORNIA.

STAMP-DISPENSING DEVICE.

Application filed March 13, 1925. Serial No. 15,394.

This invention relates to stamp dispensing devices and has particular reference to a container for holding a plurality of rolls of stamps in such a manner that a person 5 may detach one or more stamps from the roll in a most convenient manner.

Another object of this invention is to produce a device of this character which may serve to dispense various denominations of 10 stamps and which may be easily transported from place to place.

An additional object of this invention is to produce a device which will occupy but a minimum amount of space either on a 15 counter, or table while the stamps are being dispensed or during storage of the device.

A still further object is to produce a device wherein the stamps contained therein may be locked against pilfering.

20 Other objects and advantages will be apparent during the course of the following description.

In the accompanying drawings forming a part of this specification and in which 25 like numerals are employed to designate like parts throughout the same,

Figure 1 is a side elevation of my stamp dispensing device, showing the dispensing box or container superimposed upon the 30 storage receptacle,

Figure 2 is a cross section of the storage receptacle,

Figure 3 is a front elevation of the dispensing container,

35 Figure 4 is a horizontal section showing the manner of spacing the rolls of stamps, the view being taken along the line 4—4 of Figure 3,

Figure 5 is a cross section along the line 40 5—5 of Figure 3,

Figure 6 is a perspective view of two of the separator plates, and

Figure 7 is a front view showing in section one of the spools adapted to carry the 45 stamps.

It is common practice to dispense a roll of stamps from a spool, as is done in many sealing and stamping machines. It is my object, however, to provide a suitable container for a plurality of spools upon which stamp rolls are placed and fed outwardly therefrom through slots formed in the face of the dispensing device. In this manner it is possible to quickly dispense the stamps 55 and it is further possible to entirely enclose

the stamps, lock the receptacle, from unauthorized entry to the box.

In post office work it is customary for one employee to have charge of an allotment of stamps for which the said employee is accountable. Generally these stamps are left 60 in an unlocked drawer when the employee changes windows or goes off duty. With my device, it will be possible for the employee to lock and thus safeguard the stamps 65 when he leaves his position and thereby protect himself and others against suspicion.

In the accompanying drawings wherein for the purpose of illustration is shown a preferred embodiment of my invention and 70 which is illustrated to advantage in Figure 1, the numeral 3 designates a base in the form of a container, upon which I propose to superimpose a second container or receptacle 4. The container 4 serves as a storing 75 place for extra rolls of stamps when the dispensing device is placed in a safe or similar place.

It will be observed that the container 3 has hingedly connected thereto a cover 5 80 which is equipped with a portion 6 extending in parallelism with a second portion 7 formed on the container 3.

The portion 6 also serves as a shelf and as a means against which stamps may be detached from the roll while being dispensed 85 from the upper container 4.

As shown to advantage in Figure 3 the numeral 8 designates a plurality of openings formed in the container 4 through which 90 stamps are dispensed. These openings are so positioned as to be in alignment with the stamp supporting spools which will be hereinafter fully described.

The hinged cover 9 of the receptacle 4 is 95 preferably secured by a hasp 11 extending through an eye 12 through which a padlock may be passed.

It will be observed that this container 4 is superimposed on the receptacle 3 and secured thereto as by hooks 13. A carrying handle as indicated at 14 is utilized for transporting the device as a whole.

Within the container 4 I place a plurality of division plates 16. These division plates 105 are offset as shown at 17 substantially midway of their length and by arranging the plates as shown in Figure 4, it will be noted that every other pair of plates provide narrow spaces alternately at the front and rear 110

of the receptacle thus providing for the width of a roller 18 upon which stamps 19 may be coiled. These rollers are provided with hubs 21 which fit in slots 22 formed in the upper edge of the division plates 16. Thus it will be seen that it is possible to dispense stamps of various denominations from the receptacle in an efficient and expeditious manner.

My object in having a large space between the rolls in each row is to permit the operator to insert his hand for the purpose of picking up the free end of the row of stamps after the same have been shoved back into the box when locking up or when placing a new roll in the receptacle. These spaces also provide, if desired, for the storage of additional rolls so that the receptacle may also become a safe storage place for a considerable stock of stamps.

It is to be understood that the form of my invention herewith shown and described

is to be taken as a preferred example of the same, and that various changes in the shape, size and arrangement of parts may be resorted to without departing from the spirit of the invention or the scope of the subjoined claim.

Having thus described my invention, I claim:—

In a device of the character described, a receptacle, a plurality of division plates positioned in said receptacle, said division plates having an offset portion substantially midway of their length, the offset portions of each pair of division plates being bent in opposite direction from each other, a plurality of spools rotatably and removably positioned on said division plates and adapted to have their contents dispensed through slots formed in the face of said receptacle.

In testimony whereof I affix my signature.

HOMER W. KRUSE.
